UNITED STATES PATENT OFFICE

GUSTAV ZIMMERMANN, OF DUSSELDORF, GERMANY

MOLDING APPARATUS

Application filed January 23, 1931, Serial No. 510,803, and in Germany January 28, 1930.

My invention relates to apparatus for producing molds and cores for foundries, and particularly to apparatus employing compressed air to force dry sand from a 5 container into molding or core boxes.

One object of the invention is to provide a device which can be used in many ways and which attains its object by very simple means.

10 Another object of the invention is to prevent sand from sticking to its container by providing means which counteract this tendency and which require no special attendance.

15 With the foregoing and minor objects in view, the invention resides in the novel subject matter hereinafter described and claimed, the description being supplemented by the accompanying drawing, in which 20 Figure 1 is a vertical section of the device according to the invention. Figure 2 is a detail sectional view of the rod, sleeve and end connections, in which the sleeve is shown so arranged that its flange or collar 22 closes 25 the inlet opening 23 in the upper end of the container. Figure 3 is a similar view of the same in which the construction of the tube is modified so that its inlet openings 21 can be closed and the opening 23 kept open 30 so that compressed air can enter the container only through said opening 23. Figure 4 is a detail elevation of the worm bush which is fast to the rod 3. Figure 5 is a detail sectional view of the sleeve nut which 35 cooperates with the worm bush to cause the axially movable rod 3 to impart rotary movement to the tube. Figure 6 is a detail elevation of the rod, tube, guiding sleeve and sleeve nut assembly for causing the axially 40 movable rod to impart rotary movement to the tube.

In the drawing above briefly described, the numeral 1 designates a sand container to be filled with molding sand by means of an 45 attachment not shown, the container being

provided with a lower nozzle 2 adapted to be shut off by the rod 3 which can move up and down and is guided in the cover 4 of the potlike top structure 5 of the container 1. The rod 3 is connected on top with a 50 double-armed lever 6 rotatably disposed in the bracket 7 of the cover 4 and connected with a bar 8 adapted to be moved up and down by the adjustment of a lever 9, the adjustment being effected by a hand lever, 55 not shown. Normally, a spring 10 keeps the bar 8 in its highest position so that the opening of the nozzle is closed completely by the head of the rod 3.

Firmly connected with the rod 3 is a bush 60 11 having a very coarse male thread and being arranged in a nut 12 provided with a corresponding thread, the bush 11 being held axially rotatable by the cover 4 and the sleeve 13 which is axially rotatably supported by the potlike structure 5. The nut 12 has a lateral projection 14 in which a pawl 15 is held by the pin 16 so as to be loosely rotatable. The pawl 15 engages with its free end the teeth 17 of the edge 18 of the sleeve 13 wherein the tube 19 is adjustably held by the screw 20. The tube 19 is provided with the openings 21 and a circular collar 22 which fits into, and packs, the opening 23 in the top of the container 1. 70 At its lower part the tube 19 is fitted with the radial vanes 24.

When molding is to take place, compressed air is supplied to the device through the piping 25. By lowering the bar 8 and raising thereby the rod 3 the opening of the nozzle 2 is released to discharge sand into flasks or core boxes kept underneath. The action of the air is two-fold, the air passing between the bore 23 and the tube 19 having a pressing 80 effect upon the sand from above while a suction effect is created by the air which has entered, through the apertures 21, the tube 19 and is discharged from its lower end at great speed. During the upward motion of 85 90

the rod 3 the bush 11 attached to it turns the nut 12 in such a way that the pawl 15 will rotate the sleeve 13 and thus the tube 19. The vanes 24 cooperate in this motion 5 and prevent thereby that the sand sticks to the container 1.

When the tube 19 is secured in the sleeve 13 so that the collar 22 closes the opening 23, as shown in Fig. 2, compressed air can 10 enter the tube 19 only through the openings 21 and flow out at the lower end thereof with the result that it exerts in the main a suction effect upon the sand to be conveyed.

If the tube 19, as shown in Fig. 3, is 15 clamped in the sleeve 13 so high that the openings 21 are covered and the collar 22 blocks up the aperture 23, compressed air can enter the container 1 through the opening 23 only and the sand can be thrown out 20 only by the pressure exerted by the air on the top layer.

The device according to the invention makes it possible therefore to work either 25 with air pressure or suction air or both, and is thus adapted to handle all sorts of dry and molding sand under any conditions. The device may be placed directly on the flask or molding box to be filled or be arranged at a distance therefrom.

30 Should the motion of the agitator at the opening of the nozzle not suffice for very sticky dry sand, the latter can be stirred constantly by slightly and uninterruptedly lowering and raising the rod 3 during the 35 entire molding process. Furthermore, in special cases the tube 19 might be turned only during the descent of the rod 3 by disposing the pawl 15 so that it acts towards the other side.

40 Instead of the vanes 24 ordinary rods arranged radially or parallel to the tube 19, or similar means, may be employed.

I am aware that prior to my invention 45 apparatus adapted to mold directly by compressed air has been proposed already, and I do not, therefore, claim such apparatus broadly.

What I claim is:

1. The combination in a sand molding 50 machine of a closed receptacle for molding sand, having a discharge opening in the bottom, means for feeding compressed air into said receptacle, and a solid bar above the opening reciprocable vertically and 55 when in its lowermost position adapted to close the opening and prevent the discharge of sand and air from the receptacle.

2. Molding apparatus, comprising a closed 60 container for sand, having a discharge nozzle at the lower end and an air inlet opening at the upper end, an axially movable rod extending through the container to open and close the nozzle, a tube surrounding the rod, and the bore of which is of greater 65 diameter than the rod and said tube having

an air inlet opening near its upper end, and means to supply compressed air to the inlet openings of the container and the tube.

3. Molding apparatus, comprising a closed 70 container for sand, having a discharge nozzle at the lower end and an air inlet opening at the upper end, an axially movable rod extending through the container to open and close the nozzle, a vertically movable tube 75 surrounding the rod, and the bore of which is of greater diameter than the rod and said tube having an air inlet opening near its upper end shiftable into and out of connection with the air opening of the container, and means to supply compressed air to the inlet openings of the container and the tube.

4. The combination according to claim 1, 80 in which an apertured cover is provided for the container, a tube surrounds the rod and has a circular collar, the aperture in the said cover fitting the said collar.

5. The combination according to claim 1, 85 in which a tube adapted to be raised and lowered surrounds the rod, a sleeve is connected with the rod, and a guide keeps the said sleeve rotatable.

6. The combination according to claim 1, 90 in which a tube adapted to be raised and lowered surrounds the rod, a sleeve is connected with the rod, teeth are disposed on the said sleeve, a pawl is provided for the said teeth, a nut carries the pawl, and a threaded bush in the nut is firmly connected with the rod.

7. Molding apparatus comprising a closed 95 container for sand having a discharge nozzle at the lower end and an air inlet opening at the upper end, an axially movable rod extending through the container to open and close the nozzle, a revoluble tube through which the rod extends and the bore of which is of greater diameter than the rod, said tube having agitator elements and also having an air inlet opening near its upper end, means to supply compressed air to the inlet 100 openings of the container and tube, means to impart upward and downward axial movements to the rod and means operated by the rod to impart rotary movement to the tube.

8. Apparatus as claimed in claim 7, including a lever to actuate the rod, a vertically movable rod connected to said lever and a spring active on the last named rod to cause said rod and lever to normally hold the first named rod in nozzle closing position.

9. Apparatus as claimed in claim 7, including a guiding and holding sleeve in which the upper portion of the tube is secured and in which the tube has a flange 125 collar spaced from its air inlet opening and adapted to close the air inlet opening of the container when the tube is in one adjusted position.

10. Apparatus as claimed in claim 7, in
which the means to cause the rod to impart
rotary movement to the tube comprises a
worm bush fast to the rod, a sleeve nut en-
5 gaged by said worm bush, a guiding and
holding sleeve in which the upper end of the
tube is secured, said guiding and holding
sleeve being provided with ratchet teeth and
a pawl pivotally mounted on the sleeve nut
10 and engageable with said ratchet teeth.

In testimony whereof I have affixed my
signature.

GUSTAV ZIMMERMANN.
